NONDRIP FLUID DISPENSING VESSEL

Jacob G. Heim, San Gabriel, Calif.

Application July 23, 1948, Serial No. 40,212

4 Claims. (Cl. 222—571)

1

This invention relates to non-drip, fluid dispensing and containing vessels and more particularly to fluid containing vessels which have incorporated in the pouring openings thereof means adapted to prevent the dripping of fluid therefrom down the sides of the vessels when the flow of fluid through the pouring openings is curtailed or cut off by returning the vessels to their vertical position.

It is common knowledge that housewives frequently encounter difficulty with vessels containing such viscous fluids as syrup or molasses because, when the pouring of such viscous fluids from the vessels is completed, a sufficient amount of the fluid remains upon the ends or tops of the pouring openings of the vessels to permit the fluid to run down the sides and to create a sticky deposit thereupon which must be removed to prevent the soiling of the surfaces upon which the vessels rest when in storage.

It is, therefore, a primary object of my invention to provide means adapted to be incorporated in the pouring openings of a wide variety of fluid containing and dispensing vessels which are adapted to prevent the retention upon the ends or tops of the pouring openings of fluids after the pouring action has been stopped and which thus prevent the deposit of said fluids upon the sides of the containers.

Since vessels of the type referred to are frequently of a disposable nature and are thrown away when the fluid contents thereof have been exhausted, it is necessary that a drip eliminating means utilized in conjunction with the pouring openings of said vessels be easily manufactured, readily installed in association with the pouring openings, and of sufficiently moderate cost to permit the utilization of such drip eliminating means upon such disposable containers.

Another object of my invention is the provision of a non-drip element which is low in cost, may be readily fabricated, and can be incorporated upon a disposable container because the cost is so low as to be a negligible factor in the total cost of the container.

As a matter of fact, most containers or vessels for fluid usually embody a sealing means incorporated in the closure provided therefor which is adapted to seal off the contents of the vessel or container from contamination and evaporative contact with the ambient air.

It is another object of my invention to provide a drip eliminating element which is adapted to be incorporated in the closure for a container with which it is associated, which is also designed to function as a fluid seal to prevent the contamination of the contents of the vessel, and which also serves to prevent the evaporation of said contents by the ambient atmosphere.

On the other hand, there are many containers which fall in the class of multi-use containers which are adapted to be reused over and over again until the container is so damaged that it no longer can properly perform the function for which it was originally intended. Typical of

such containers are milk bottles, motor oil containers, and a wide variety of similar vessels. It is particularly desirable that such containers be provided with a drip eliminating means adapted to prevent the dripping of the fluids contained therein down the side of the bottle or container, since the good will engendered toward the purveyor of the material enclosed within the container by the association therewith of the drip eliminating element will be a considerable factor in encouraging the recurrent purchase of that particular brand of the product. Since containers of this type frequently utilize temporary but effective discardable closure means, it is desirable to provide a drip eliminating means which will also serve as a seat for said closure means.

A further object of my invention is the provision of drip eliminating means adapted to be utilized with containers which are designed to serve a multi-use purpose and which is provided with an integral seat adapted to receive a reusable or discardable closure means or cap designed to seal off the contents of the container from contamination or contact with the ambient atmosphere.

Since most of the difficulty encountered by housewives is in the pouring of such viscous or oily fluids as cream, salad oil, syrup, molasses, or the like, it is desirable to provide a pouring vessel such as a pitcher or cruet in which such fluids are stored for table use having embodied permanently therein a drip eliminating element provided in accordance with my invention.

It is, therefore, a further object of my invention to provide a pitcher or cruet, or similar table service device, having permanently inserted in the pouring opening thereof a drip eliminating element adapted to prevent the retention at the pouring opening of the fluid contained therein when the pouring action has ceased.

Other objects and advantages of my invention will become apparent from a consultation of the following specification and the accompanying drawing, which is for the purpose of illustration only, and in which:

Fig. 1 is a perspective view showing a typical disposable container adapted to be utilized as a container for syrup, molasses, or the like, and having associated therewith the disposable form of my invention;

Fig. 2 is an enlarged, vertical sectional view taken on broken line 2—2 of Fig. 1, and showing the pouring opening of the vessel with fluid being poured therethrough;

Fig. 3 is an enlarged sectional view similar to Fig. 2 and showing the pouring opening of the vessel after the pouring action had ceased with the vessel in the erect position;

Fig. 4 is a fragmentary sectional view showing the incorporation in the pouring opening of a multi-use container or vessel of a drip eliminating element;

Fig. 5 is a top plan fragmentary detail view

showing the incorporation in the lip of a pitcher of a drip eliminating element; and

Fig. 6 is a fragmentary sectional view taken on line 6—6 of Fig. 5.

Referring to the drawing, I show a single use, disposable container 10, such as is intended to serve as a receptacle for syrup, molasses, salad oils, and similar fluids, which have a tendency, when poured from the opening of such a vessel, to be retained at the edge of the opening and to drip down the side of the vessel when the pouring action is completed. The fluid containing and dispensing vessel 10 includes a base portion 11 and a generally cylindrical side wall 12, which terminates in a neck portion 13, which provides a pouring opening 14 adapted to permit the dispensing of fluids from the vessel.

The neck portion 13 includes an inner surface 15, an outer surface 16, and an end surface 17. In the act of pouring, the fluid passes over the inner surface 15 as it flows through the pouring opening 14, contacts the end surface 17 and, frequently, adheres to the end surface 17 and drips down the outer surface 16 when the pouring action has been completed.

In order to prevent the dripping of the fluid remaining on the end surface 17 of the pouring opening 14, the container is provided with an annular pouring element 18 having a central opening 19 adapted to permit the passage of fluid therethrough. In the present embodiment of my invention, the pouring element 18 comprises a ring or annulus of flexible material, such as paper, which is coated with a wax, or similar substance, which is unwettable by the fluid being poured from the container.

The pouring element 18, which is adapted to prevent the dripping of fluid down the sides of the container when the pouring action has been terminated, is designed to be incorporated in the closure, not shown, and to supplant the customary seal ordinarily utilized to seal off the pouring opening and the contents of the vessel from contamination and contact with the ambient air. The pouring element 18 secured to the end surface 17 of the pouring opening 14 by means of glue provided on the under side of the pouring element 18, but any conventional adhesive may be utilized to secure the pouring element 18 to the end surface 17. When the closure is removed from the pouring opening 14, the pouring element 18 remains upon the end surface 17 of the pouring opening 14 and serves to eliminate the dripping tendency encountered in the pouring of the aforementioned fluids. In addition, it also serves, when the closure is applied, the function of sealing off the contents of the vessel from contamination and contact with the ambient air. Since it is constructed of paper, and since it serves the aforementioned dual function, it is obvious that the cost of incorporating such an element in a disposable container is negligible and will closely approximate that of conventional seals ordinarily incorporated in the closures of such containers.

As may be best seen in Figs. 2 and 3 of the drawing, the inner edge of the pouring element 18 overlaps the inner edge of the end surface 17 and the outer edge of the pouring element overlaps the outer edge of the end surface 17 of the neck portion 13 of the container 10. However, it is possible that the pouring element be so dimensioned that the inner and outer edges thereof be substantially flush with the inner and outer edges of the end surface 17. The pouring

element 18 is so disposed upon the end surface 17 of the neck 13, which provides the pouring opening 14, that the inner and outer edges thereof extend radially of the vertical axis of the container 10, and thus permits the overlapping relationship of the inner and outer edge portions thereof in relation to the end surface 17 of the neck 13.

Another embodiment of my invention is shown in Fig. 4 and is adapted to be incorporated in the neck portion 23 of a multi-use container, such as a milk bottle, and which may be permanently positioned thereupon if desired. The neck portion 23 of the multi-use container, not shown in full, provides a pouring opening 22 which is defined by an inner surface 24, an outer surface 25, and an end surface 26.

A pouring element 27, which in the present embodiment is in the form of an annular cap 28 incorporating a central opening 29, is positioned in the pouring opening 22 of the neck portion 23, and includes a downstruck inner edge portion 32, and a downstruck outer edge portion 33. The downstruck inner edge portion 32 overlaps the end surface 26 of the neck portion 23 and contacts the inner surface 24 of the neck portion 23. The downstruck outer edge portion 33 overlaps the end surface 26 of the neck portion 23 and contacts the outer surface of the neck portion. Thus, a secure installation of the pouring element 27 within the pouring opening 22 is provided.

Since containers such as the one under discussion must be sterilized before being reused, in many instances, it is desirable to provide a pouring element 27 which is of such a nature that it can be firmly affixed to the neck portion 23 of the container and which yet can be readily removed prior to the sterilization process and subsequently installed upon the neck portion 23 when the sterilization process has taken place. If desired, the pouring element 27 may be sterilized by a process which will not inhibit the efficiency of the drip eliminating function thereof. For example, the pouring element 27 may be formed of a plastic substance having resilient characteristics which will cause it to cling to the neck portion 23 of the container, and which will also be unwettable by the fluid which is ordinarily dispensed from said container.

As may be readily discerned from Fig. 4 of the drawing, the downstruck inner edge portion 32 and the downstruck outer edge portion 33 extend downwardly substantially axially of the vertical axis of the pouring opening 22. To facilitate the closing of the container by means of a conventional milk bottle cap 35, or similar closure, the downstruck inner edge portion 32 of the pouring element 27 is provided with an annular groove 34 adapted to receive the edge of the cap 35. However, if it is desired to close the pouring opening 22 by a stopper closure 36 it is easy to do so since that portion of the pouring element 27 provided by the downstruck inner portion 32 below the annular groove 34 will provide sufficient surface to permit a close seal to be made between it and the stopper closure 36 and to prevent the contamination of the contents of the container.

One of the most annoying facets of the dripping problem involved in the dispensing of such fluids, as indicated above, arises when the pouring of such fluids is attempted at the table from such vessels as pitchers and cruetts adapted for the temporary storage of the fluids. There is shown in Figs. 5 and 6 of the drawings an em-

bodiment of my invention adapted to prevent the dripping of fluid from the lip of a pitcher or a cruet when the pouring thereof has been terminated. The pitcher lip 38 is substantially of arcuate configuration and is constituted by an inner surface 39, an outer surface 41, and an end surface 42. Permanently installed in the pitcher lip 38 and adapted to prevent the dripping of fluid therefrom is a pouring element 43, which is formed from a material which is unwettable by the fluid which is usually stored in and dispensed from the container. The pouring element 43 includes an inner edge portion 44 and an outer edge portion 45. The inner edge portion 44 overlaps the inner surface 39 of the pitcher lip 38, and the outer edge portion 45 overlaps the end surface 42 of the pitcher lip 38 and may also, if desired, overlap the outer surface 41 of the pitcher lip. When fluids are dispensed from a container provided with such an element as the pouring element 43, the passage of fluid therover in the dispensing process will naturally occur. However, when the pouring action is terminated, any drops of fluid which might have a tendency to accumulate upon the pouring element are unable to adhere thereto and are returned into the body of the container, thus preventing the accumulation of such drops and their subsequent dripping down the side of the container.

I thus provide by my invention a pouring element which is adapted to be incorporated upon disposable containers, multi-use containers, and in permanent dispensing vessels, and which is adapted to prevent the accumulation of drops of the fluid dispensed therefrom upon the end surface of the pouring opening thereof, thus preventing the dripping of such retained fluids down the sides of the vessels when the pouring action has been completed.

The various pouring elements disclosed are adapted to be incorporated in a wide variety of fluid containing and dispensing vessels, and are susceptible of being manufactured from a wide variety of materials which are substantially unwettable by the fluid which it is intended be stored in and dispensed from the vessels. Such pouring elements, as indicated above, may be of a disposable, semi-permanent, or permanent nature depending upon the application in which the pouring element is utilized. Pouring elements also may be provided with means adapted to permit the reception thereby of closure means to close the vessel, or may be designed to serve the auxiliary function of a sealing means in conjunction with said closure means.

Although I have shown and described preferred embodiments of my invention, it will be understood that certain portions thereof may be changed to perform the same function without departing from the spirit of my invention and, therefore, I do not intend to be limited by the specific form described, but desire to be accorded the full protection of the following claims.

I claim as my invention:

1. In combination: a fluid containing and dispensing vessel, said vessel having a base portion and a side wall defining a fluid containing chamber, said side wall terminating in a pouring opening to permit fluid to be dispensed from said vessel, said pouring opening having an inner edge and an outer edge and a top wall defining the termination of said side wall; and an unwettable pouring element adapted to be secured about said pouring opening comprising an annular disc having an inner edge portion overlapping the inner

edge of said opening and a outer edge portion overlapping the outer edge of said opening, said inner and outer edge portions lying in substantially the same horizontal plane.

5 2. In combination: a fluid containing and dispensing vessel, said vessel having a base portion and a side wall defining a fluid containing chamber, said side wall terminating in a pouring opening to permit fluid to be dispensed from said vessel, said pouring opening having an inner edge and an outer edge and a top wall defining the termination of said side wall; and an unwettable pouring element adapted to be secured to said pouring opening comprising an annular disc having an inner edge portion and an outer edge portion, said inner edge portion overlapping the inner edge of said opening and said outer edge portion overlapping the outer edge of said opening, said inner and outer edge portions of said annular disc extending substantially radially of the vertical axis of said opening and lying in substantially the same horizontal plane.

25 3. In combination: a fluid containing and dispensing vessel, said vessel having a base portion and a side wall defining a fluid containing chamber, said side wall terminating in a pouring opening to permit fluid to be dispensed from said vessel, said pouring opening having an inner edge and an outer edge and a top wall defining the termination of said side wall, at least a portion of said pouring opening being of substantially arcuate conformation; and an unwettable pouring element adapted to be secured about said pouring opening having an inner edge portion overlapping the inner edge of said opening and an outer edge portion overlapping the outer edge of said opening, said inner and outer edge portions lying in substantially the same horizontal plane.

30 4. In combination: a fluid containing and dispensing vessel, said vessel having a base portion and a side wall defining a fluid containing chamber, said side wall terminating in a pouring opening to permit fluid to be dispensed from said vessel, said pouring opening having an inner edge and an outer edge and a top wall defining the termination of said side wall, at least a portion of said pouring opening being of substantially arcuate conformation; and an arcuate, unwettable pouring element adapted to be secured about said pouring opening having an inner edge portion overlapping the inner edge of said opening and an outer edge portion overlapping the outer edge of said opening, said inner and outer edge portions lying in substantially the same horizontal plane.

55 JACOB G. HEIM.
